Inventor:
Alfred Derschke

UNITED STATES PATENT OFFICE

ALFRED DIERSCHKE, OF ESSEN, GERMANY, ASSIGNOR, BY MESNE ASSIGNMENTS, TO THE KOPPERS COMPANY OF DELAWARE, OF PITTSBURGH, PENNSYLVANIA, A CORPORATION OF DELAWARE

APPARATUS FOR THE DRY COOLING OF COKE

Application filed December 14, 1931, Serial No. 580,949, and in Germany December 10, 1930.

An application has been filed in Germany Dec. 10, 1930.

My invention relates to the dry cooling of coke and more particularly to the type of coke cooling in which the coke is cooled in a totally enclosed chamber by means of cold inert gases which after being brought into contact with the hot coke are passed over pipes through which flows a cooling agent, preferably water, whereby the inert gases are cooled and then reutilized for cooling the coke.

One object of my invention is to provide improvements in apparatus for the dry cooling of coke which enable the dry cooling of coke, particularly of coke produced in a coke oven battery equipped with horizontal coking chambers, to be carried out in a particularly economical manner.

According to my present invention for cooling the glowing coke expelled from the coking chambers I employ a steeply inclined drum provided at both ends with closable openings, the said drum being movably disposed in front of the coke oven battery similarly to the ordinary coke quenching trucks, so that the coke expelled from one of the coking chambers of the battery can be slid directly through the upper opening into the cooling drum which has been run up to the said coking chamber, and after cooling can be ejected through the lower opening of the cooling drum at any required point along the track.

This particular construction of the cooling drum does away with the relatively expensive apparatus and devices hitherto used for transferring the glowing coke from the coking chamber into the cooling drum and for removing the cooled coke from the drum. Furthermore, with my arrangement I obtain a substantial saving of coke, as the coke does not have to be loaded and unloaded several times as hitherto, whereby the larger pieces of coke are easily broken. Finally, in my arrangement the loss of coke by combustion is very small, as the glowing coke only comes into contact with the air for a short period of time. These technical advantages give a

higher yield of coke and a more valuable product than heretofore.

A further object of my invention is to provide improvements in the container serving to cool the coke, in order to obtain a more efficient and economic cooling of the coke than heretofore.

According to my present invention there is provided in the drum serving to cool the coke a series of channels or pipes arranged in the manner of a tubular steam boiler and flowed through by a liquid, a space being left between the said pipes for receiving the glowing coke. Preferably according to my invention this space between the coolers is of dimensions which entirely or approximately correspond to the dimensions of the coking chamber in which the coke was made. This latter feature is advantageous in order to prevent the coke cake splitting or the larger pieces of coke breaking when the coke cake is being transferred from the coking chamber into the cooler. For this purpose it is also of advantage to provide the cooling drum with means for bringing it into a horizontal or almost horizontal position during the introduction of the coke cake. For supporting the coke and saving the tubes it is preferred to provide in the space between the cooling tubes for receiving the coke a channeled bed in the bottom of which openings are provided which permit the passage of inert gases through the glowing coke.

I also provide the cooling drum with means for withdrawing the inert gases at the top of the drum after passing over the coke, and for returning same to the openings in the channeled bed after having been cooled.

In order to facilitate the passage of inert gases through the glowing coke, it is also preferable to provide on the bed a flue or channel of approximately box shape, in the sides of which openings for the passage of gas are provided. These gas passages are adequately protected against blockage by particles of coke.

In the apparatus according to the invention the heat of the glowing coke is transmitted partly by radiation and partly by convection to the tubes of the cooling drum through

which the cooling agent flows. Water is preferably used for cooling the tubes, and the whole cooling apparatus can with advantage be used for producing hot water.

5 Thus a further object of my invention is to provide means for utilizing the above described coke cooler for preparing hot water which can be passed from the coke cooling apparatus to remote places for use.

10 For this purpose I provide parallel to the track of the cooling apparatus channels or gutters for supplying and removing cold and hot water into which projects the cold water supply pipe of the cooling drum or the 15 hot water discharge pipe of the cooling drum. A pump is also provided in the cooling apparatus in order to pump cold water out of one channel through the cooling tubes of the drum and to force the hot water into the other 20 channel.

In order to decrease the heat loss of the hot water inside the water gutters or channels they are provided with heat insulation. They are also preferably covered in at the top and 25 the cover is provided with apertures through which the preferably telescopic ends of the supply and discharge pipes of the cooling drum may be sunk.

It is also preferred to provide these apertures with flaps which open automatically when the pipes are lowered into the apertures.

Finally it is possible to cover the gutters or channels throughout their whole length with hinged lids which when the apparatus 35 is in operation are opened automatically by projections having a form similar to a ploughshare which are provided on the ends of the pipes dipping into the channels, and which close automatically by their own 40 weight.

With these and other objects of the invention in view I will now describe the nature of the present invention on the lines of the accompanying drawings in which:

45 Figure 1 is a vertical longitudinal section and partial side elevation through a coke cooling apparatus constructed in accordance with the invention,

Figure 2 is a vertical cross-sectional view 50 illustrating the channels or gutters for the passage of the cooling water in the closed position and

Figure 3 is a vertical cross section and partial side elevation of the apparatus according 55 to Fig. 1.

In the apparatus illustrated in the drawings the coke is made in an ordinary horizontal oven chamber 1 into which the coal which is to be coked can be charged at the 60 top through openings 2. Beneath the coking chamber regenerators 3 for warming air and, if required, fuel gas are provided which are utilized for heating the walls of the coking chambers.

65 The coking chamber 1 has openings on

both ends which can be closed by means of doors 4. In front of the coking chamber a trolley 6 runs on wheels 7 on a platform 5, the said trolley carrying two walls 9 consisting of cast iron plates 8 or the like and disposed at a distance from each other approximately equal to the width of the coking chamber.

A device for drawing back the door 4 of the coking chamber is also provided on the side of the trolley 6 near the guide walls 9. Only the arms 10 for lifting the door are illustrated in the drawings. When the coal in one of the chambers 1 has been completely transformed into coke and is therefore ready to be withdrawn from the chamber, the trolley is run up before the door of the chamber so that the arms 10 can engage beneath projections 11 of the door 4. The door is then withdrawn from the door opening of the chamber and the trolley moved sideways so that the opening between the two walls 9 is right in front of the chamber opening.

Then as usual the coke cake inside the chamber 1 is pushed out from the other end of the chamber, and moves between the walls 9 of the trolley 6, whereby it is prevented from breaking to pieces. As when the coke cake is pushed through the space between the guides 9 of the trolley 6 there is a risk owing to the large amount of friction set up by the cake that the trolley will tip over, one or more rollers 12 are provided on the superstructure of the trolley 6 which apply themselves against a bar 13 firmly attached to the oven battery.

As illustrated in Fig. 1, the guide walls of the trolley 6 are bent downwards on the outside.

Alongside the track 5 for the trolley 6 longitudinally of the coke oven battery a second track 14 is provided on whose rails 15 a travelling frame 17 carrying the drum 18 for cooling the coke is adapted to run on wheels 16.

This cooling drum which is covered with a material 19 which is a bad conductor of heat is disposed at an angle on the travelling frame 17, the angle being such that the coke which has been introduced into the cooling drum can slide automatically out of the container.

The cooling drum 18 has an approximately cylindrical cross-section and at each end an opening 20 or 21. The upper opening 20 can be closed by means of a lid 22 which is oscillatable on a shaft 23 for the purpose of closing the opening 20. The shaft 23 is rotatable in bearings 24 and carries on the outside a bevel wheel 25, which through the intermediary of another bevel wheel 26 and a transmission gear 27 is connected with a hand crank 28 in such a manner that when the crank 28 is rotated the shaft 23 rotates and the lid 22 can thereby be opened or closed.

The opening 20 of the cooling drum 18 is of such form that the coke cake expressed between the walls 9 of the trolley 6 can slide into the interior of the cooling drum 18 over the steeply inclined lateral projection 29 of the trolley 6. For supporting this process the drum 18 has a second projection 30 extending to beneath the projection 29 of the trolley 6, which prevents the coke falling through the space between the drum and the trolley.

The lower opening 21 of the drum 18 can be closed by means of a lid 31 which is hingedly connected to a lever 33 oscillatable about the point 32. The lever 33 carries pivotally at its outer end a locking lever 34 whose nose 35 when the lever 34 is closed lies against a projection 36 of the cooling drum under the action of a weight secured to the lever 34.

A hand wheel 39 acting on a screw threaded spindle 38 serves to open the flap 31. The screw-threaded spindle 38 is connected at its lower end with a lever arm 40 which is connected at 32 to the lever 33 and adapted to move between limits. The lower end of the spindle 38 is also connected through the rod 41 with the locking lever 34. The connection between the screw-threaded spindle and the lid lever 33 and the locking lever 34 is so formed that when the spindle 38 moves upwards the lever 34 is first of all so oscillated that its nose 35 is moved away from the lock projection 36 of the drum. As the spindle 38 continues to move the lid lever 33 and therewith the lid 31 are swung upwards by means of the lever arm 40, until the lower opening 21 of the cooling drum is completely free. On the other hand, when the opening 21 is being closed, the lid is pressed firmly against the lower opening of the drum by means of the lever arm 40, whereby the locking lever 34 can yield until its nose 35 engages against the projection 36 of the cooling drum.

As is particularly evident from Fig. 3, a series of tubes 42 are provided in the interior of the cooling drum 18, with a space 43 between them for receiving the coke which is introduced into the drum. For protecting the lower cooling tubes 42 from being flattened a fluted support 44 is provided in the cooling drum, whose lateral walls 45 are constructed in the manner of a venetian blind. On the coke bed support 44 an upwardly projecting channel 46 of approximately box-shaped section is also provided in the vertical sides of which openings 47 are provided.

As already stated the glowing coke introduced into the cooling drum gives up its heat to the cooling tubes 42 by radiation and convection. For this purpose inert gases are passed through the channel 46 and openings 47 into the coke bed by means of a fan 48 driven by a motor 49, the said fan being connected on the one hand through the pipe 50

with the lower end of the channel 46 and on the other hand through the pipe 51 with a connecting pipe 52 provided at the upper end of the drum 18. The cooling gases are thus first forced into the channel 46, escape therefrom through the lateral openings 47, flow through the hot coke lying on the bed support 44, and then flow alongside and in contact with the outer surface of the upper tubes 42.

The cooling tubes 42 are secured at their upper and lower ends in tube heads 53 in the manner of a tubular steam boiler. Through the tubes 42 a cooling liquid preferably cold water is passed, which flows out of the elevated reservoir 55 which is disposed in the upper part of the traveling frame 17 above the cooling drum, and enters the lower tube head 53 through a pipe 54. The cold water is withdrawn by means of a pump 56 through a pipe 57 from a stationary gutter or channel 58 disposed along the track of the drum trolley. The pump 56 is connected by the pipe 59 with the supply tank 55. The hot liquid or hot water is withdrawn at the upper end of the cooling drum from the upper tube head 53 through the pipes 60 and then flows through the pipe 61 to a stationary gutter 62 provided near the gutter 58. The pipes 61 and 57 are firmly connected with the cooling drum trolley and during the movement of the said trolley move to and fro in the stationary gutters 58 and 62.

As a protection against dirt and to prevent loss of heat the gutters 58 and 62 are covered with a series of gutter lids or flaps 63 which are hingedly mounted on the side walls of the gutters by means of hinges 63'. For opening the flaps 63 projections 64 are provided on the lower ends of the tubes 61 and 57. The arrangement is such that as the drum trolley moves along the flaps covering the gutters 58 and 62 are opened one after another by the projections 64 and close automatically after the projections 64 when the trolley 6 moves further on.

In the cooling drum constructed in accordance with the present invention a rapid and efficient cooling of the coke may be obtained with a great saving of coke. By practical tests I have found that as a general rule a period of 1½ hours is sufficient with a normal size of coking chamber to cool one charge thereof to the desired low temperature. In certain cases it may be preferable to provide a number of cooling drum trolleys between the coke oven battery and gutters 58, 62, or one trolley with a number of cooling drums. The construction of the trolley in the latter case is the same as that herein described.

In utilizing the apparatus according to this invention for cooling coke, after opening the upper drum lid 22 and closing the lower lid 31 the trolley is run up beneath the guiding trolley 6 so that the coke cake slides directly

from the trolley 6 into the drum 18. When the contents of the coking chamber 1 have been entirely removed into the cooling drum 18, the cooling drum trolley is moved aside 5 a little and the lid 22 closed.

After the coke has remained in the cooling drum for the necessary time and the desired temperature has been reached, the cooling drum trolley is run beneath an expeller of 10 suitable construction which is not shown in the drawings, and the lower lid 31 is opened, whereupon the coke emerges automatically from the cooling drum.

It is to be understood that I do not desire 15 to be limited to the exact details shown and described, for obvious modifications will occur to a person skilled in the art.

I claim:

1. The combination with a coke oven battery comprising coking chambers and coke conveyor rails extending longitudinally of the battery opposite the coking chambers for the conveyance of coke from the coking chambers, of a carriage adapted for being 20 propelled along said rails, a steeply inclined closed dry cooling coke container mounted on said carriage and provided with upper and lower closable coke inlet and outlet openings for receiving hot coke from the coking 25 chambers; means cooperating with said container and carried therewith by said carriage for effecting a recirculation of an inert cooling gas through hot coke in said container, and means carried with said container by 30 said carriage and adapted for cooling the recirculating inert coke cooling gas by indirect heat exchange.

2. The combination with a coke oven battery comprising coking chambers and coke 40 conveyor rails extending longitudinally of the battery opposite the coking chambers for the conveyance of coke from the coking chambers, of a carriage adapted for being propelled along said rails, a steeply inclined 45 closed dry cooling coke container mounted on said carriage and provided with upper and lower closable coke inlet and outlet openings for receiving hot coke from the coking chambers; means cooperating with said container 50 and carried therewith by said carriage for effecting a recirculation of an inert cooling gas through hot coke in said container, and means carried with said container by said carriage and adapted for cooling the recirculating 55 inert coke cooling gas by indirect heat exchange, said last mentioned means comprising a tube boiler for circulation of hot water in indirect contact with the circulating inert coke cooling gas.

3. The combination with a coke oven battery comprising coking chambers and coke conveyor rails extending longitudinally of the battery opposite the coking chambers for the conveyance of coke from the coking 65 chambers, of a carriage adapted for being

propelled along said rails, a steeply inclined closed dry cooling coke container mounted on said carriage and provided with upper and lower closable coke inlet and outlet openings for receiving hot coke from the coking chambers, a group of water tubes arranged annularly within said container so as to form a central coke receiving and containing chamber in line with said coke inlet and outlet openings; and means carried with said container by said carriage for recirculating an inert gas through said coke chamber and through the spaces between said water tubes in closed cycle.

4. The combination with a coke oven battery comprising coking chambers and coke conveyor rails extending longitudinally of the battery opposite the coking chambers for the conveyance of coke from the coking chambers, of a carriage adapted for being propelled along said rails, a steeply inclined closed dry cooling coke container mounted on said carriage and provided with upper and lower closable coke inlet and outlet openings for receiving hot coke from the coking chambers, a group of water tubes arranged annularly within said container so as to form a central coke receiving and containing chamber in line with said coke inlet and outlet openings; and means carried with said container by said carriage for recirculating an inert gas through said coke chamber and through the spaces between said water tubes in closed cycle, and means carried with said container by said carriage for effecting circulation of water through said tubes, said latter means including a supply drum mounted above said container at an elevation above said tubes.

5. The combination with a coke oven battery comprising coking chambers and coke conveyor rails extending longitudinally of the battery opposite the coking chambers for the conveyance of coke from the coking chambers, of a carriage adapted for being propelled along said rails, a steeply inclined closed dry cooling coke container mounted on said carriage and provided with upper and lower closable coke inlet and outlet openings for receiving hot coke from the coking chambers, a group of water tubes arranged annularly within said container to form a central coke receiving and containing chamber in line with said coke inlet and outlet openings, a coke bed support mounted in the coke containing chamber over the water tubes in the lower part thereof and inclined from the coke inlet to outlet; a closed longitudinal channel on the upper portion of said support and having upwardly directed walls with inert gas outlet ports therein for passage of inert gas into the coke chamber, means carried with said container by said carriage for withdrawing inert gas from around the tubes in the upper part of the container and returning such gas directly into said channel.

6. The combination with a coke oven battery comprising coking chambers and coke conveyor rails extending longitudinally of the battery opposite the coking chambers for the conveyance of coke from the coking chambers, of a carriage adapted for being propelled along said rails, a steeply inclined closed dry cooling coke container mounted on said carriage and provided with upper and lower closable coke inlet and outlet openings for receiving hot coke from the coking chambers, a water tube boiler carried by said carriage, means carried by said carriage for effecting a recirculation of inert coke-cooling gas through said container and in contact with said water tubes, a plurality of stationary gutters arranged parallel to said rails, means for circulating water through said tube boiler, said means being carried by and movable with said carriage and including two conduits comprising a water inlet conduit dipping into one of said gutters to receive water therefrom and an outlet conduit dipping into the other gutter to discharge hot water thereto.

7. Apparatus as claimed in claim 6, and in which self-closing movable closure lids are provided on the gutters which are adapted to be opened by the inlet and outlet conduits as they are moved along the gutters by the carriage.

8. Apparatus as claimed in claim 6, and in which self-closing oppositely disposed hinged gutter lids are provided on each of the gutters which are adapted to be opened by the movement of the inlet and outlet conduits between the lids as the conduits are moved along the gutters by the carriage.

9. Apparatus as claimed in claim 6, and in which self-closing oppositely disposed hinged gutter lids are provided on each of the gutters which are adapted to be opened by the movement of the inlet and outlet conduits between the lids as the conduits are moved along the gutters by the carriage, and in which the dipping portions of the conduits are provided with outwardly flaring projections for effecting the opening of the gutter lids.

10. The combination with a coke oven battery comprising coking chambers, two parallel tracks provided longitudinally of the battery opposite the coking chambers at one side of the battery, of a plurality of gutters parallel to said tracks, a truck on the inner track and propelled therealong from chamber to chamber and having two guiding walls for guiding coke extracted from the respective coking chambers, a carriage adapted to be propelled along the outer track, a closed dry cooling coke container mounted on and

movable with said carriage and having a steeply inclined coke bed support therein and upper and lower closable coke inlet and outlet doors for receiving and discharging coke from said truck, means carried with said container by said carriage for recirculating an inert cooling gas through coke in said container, a tubular boiler in said container for absorbing heat from coke therein and located in the path of the inert gas recirculated by the recirculating means therefor, means for effecting a forced circulation of cooling water through said tubular boiler, said means being carried with said container by said carriage and including a hot water outlet conduit dipping into one of said gutters and a cool water inlet conduit dipping in the other gutter, both said conduits being movable lengthwise within said gutters as the carriage is propelled alongside the battery on the track therefor from chamber to chamber.

11. The combination with a coke oven battery comprising coking chambers, two parallel tracks provided longitudinally of the battery opposite the coking chambers at one side of the battery, of a plurality of gutters parallel to said tracks, a truck on the inner track and propelled therealong from chamber to chamber and having two guiding walls for guiding coke extracted from the respective coking chambers, a carriage adapted to be propelled along the outer track, a closed dry cooling coke container mounted on and movable with said carriage and having a steeply inclined coke bed support therein and upper and lower closable coke inlet and outlet doors for receiving and discharging coke from said truck, means carried with said container by said carriage for recirculating an inert cooling gas through coke in said container, a tubular boiler in said container for absorbing heat from coke therein and located in the path of the inert gas recirculated by the recirculating means therefor, means for effecting a forced circulation of cooling water through said tubular boiler, said means being carried with said container by said carriage and including a hot water outlet conduit dipping into one of said gutters and a cool water inlet conduit dipping in the other gutter, both said conduits being movable lengthwise within said gutters as the carriage is propelled alongside the battery on the track therefor from chamber to chamber, and both said gutters being disposed at an elevation above the outlet door for discharge of coke beneath the gutters.

In testimony whereof I have hereunto set my hand.

ALFRED DIERSCHKE.
